LADY'S BLOUSE OR THE LIKE

Beatrice Donin, New York, N. Y.

Application March 24, 1947, Serial No. 736,812

8 Claims. (Cl. 2—106)

1

The present invention relates to an article of apparel, and more particularly to a lady's blouse or waist, or the like garment.

Blouses, waists, or similar garments of the type to which the present invention relates, which are generally worn in association with a skirt, guimpe, slacks, or the like, have certain disadvantages or shortcomings which tend to detract from the appearance and comfort of the wearer. Such blouses or the like tend to respond to and follow the tensions and stresses set up by the movement of the wearer's body. As a result, the blouse or the like tends to creep on the body and to become displaced and disarranged thereon. Frequently, such displacement and disarrangement proceeds to the extent that there is a separation between the blouse and the skirt or the like, at the waistline, resulting in a very untidy and unattractive appearance.

It is an object of the invention to provide a blouse, waist, or the like, of the character described, in which the forces, tensions and stresses set up by body movements will be resisted and the blouse or the like will be maintained substantially in its original position on the body, so that it will not creep or shift on the body and will not become disarranged thereon and its tails will not creep out of or become separated from the skirt or the like at the waistline.

It is an object of the invention to provide a garment of the character described having associated means for resisting the force of the tensions and stresses of body movement.

It is an object of the invention to provide a garment of the character described in which the means for resisting the force of the tensions and stresses set up by body movement are highly efficient for their purpose, and are located at the most advantageous position for their purpose.

It is an object of the invention to provide a garment of the character described having means of simple construction for resisting the force of the tensions and stresses set up by body movement which means are economical to produce, easy and convenient to use, and comfortable to wear.

The foregoing and other advantages and superiorities of the garments of the present invention will become more readily apparent to those skilled in the art from the embodiment thereof shown in the accompanying drawing and from the description thereof following. It is to be understood, however, that such embodiment is shown by way of illustration only, to make the principles and practice of the invention more readily comprehensible, and without any intent

2

of limiting the invention to the specific details therein shown.

In the drawings:

Fig. 1 is an elevational view of a blouse embodying the present invention, as viewed from the inside thereof, one casing for the resisting means being broken away, to disclose details of the tension force resisting means;

Fig. 2 is a more or less diagrammatic view, in perspective, of such blouse as worn on a body, the blouse and the body being shown by broken lines, with the tension force resisting means of the invention shown in solid lines;

Fig. 3 is a section taken on line 3—3 of Fig. 1, to enlarged scale; and

Fig. 4 is a view similar to Fig. 3, but taken at the position of line 4—4 of Fig. 1.

Referring more specifically to the accompanying drawings, the blouse, generally designated as

20 10, although shown as being of the back buttoning type, may be of any desired type, style or form and of any desirable, suitable material or fabric. As illustrated, the blouse 10 comprises the front panel, 11, and the rear panels, 12, joined to the 25 front panel 11 at the sides of the blouse, as by seams 13, in the conventional manner. The edges of the rear panels, 12, may be provided with conventional, cooperating fastening means, such as the buttons, 14, and the button holes, 15.

30 The blouse 10 is also provided with armholes, 16, into which may or may not be fitted sleeves, 17, which may be of any desired style or length, and may be secured to the body of the blouse by 35 seams, 18.

I have observed that the bending and twisting of the torso and raising of the arms set up the greatest strain and tension forces under the arm, at the location of the side seams, 13, of the blouse, such strains and tensions being transmitted to 40 such seam through the armhole seams, 18. In making the blouse of the present invention, therefore, I have provided means for setting up a counteracting or resisting force at the points of strain and tension, namely, under the armhole, at the 45 side of the blouse, at the location of the seams 13.

Such counterbalancing or resisting force exerting means may comprise a resilient element permanently connected by one end to the armhole edge, at or about the location of the side seam, and connectable at the other end to the body of the wearer at the waistline.

In the embodiment illustrated, the resisting force exerting means comprises an elastic band, 20, approximately twice the length of the distance from the armhole to the waistline, asso-

ciated with each armhole. Each band is folded over and connected by its free ends, 21, to its armhole seam, 18, preferably with one of the ends on each side of the side seam 13, so as to counteract front and rear tension forces.

A tie-band, 22, is connected to each elastic band 20, at its fold, 23, such tie-band being freely fulcrumed on the blouse, at the waistline, to permit its extension, either forwardly or rearwardly, around the waist. As shown in Fig. 2, the ends of bands 22 are tied together, to bring the elastic band to bear upon the body of the wearer.

While the fulcrum means may comprise any suitable device, such as a fabric or metal loop secured to the blouse, through which the tie-band, 22, may be freely passed, I prefer to use the means illustrated, combining a protective covering for the elastic band 20 as well as a fulcrum. Such means comprises a tubular sheath, 24, which may taper downwardly and may preferably be formed of the same or similar material as the blouse, particularly as to color. The upper end of the sheath 24 may be connected, together with the ends, 21, of the band, 20, to the armhole seam, 18. The lower end of the sheath 24 is open, as at 25, to permit free passage therethrough of the tie-band, 22, which is connected to the elastic band 20 arranged within the sheath 24. The lower portion of the sheath, 24, is connected by its edges to the blouse, 10, as by stitching 26, so that the edges of the opening 25, may serve as the fulcrum for the tie-band 22, passing therethrough.

It will be readily apparent that by the means provided, the tension forces usually set up in the sides of the garment by body movement will be resisted by the elastic bands, which are connected to the armhole seam at one end, and to the body at the other end by the tie-bands. Thus, the elastic bands will resist vertical strains and tensions and the tie-bands will resist horizontal stresses and tensions, both forces meeting at the point of fulcrum.

It will also be apparent that many modifications and variations may be made in the garments of the present invention, all in accordance with the principles of the invention hereinabove set forth.

What I claim is:

1. In combination with a garment of the shirt or waist type constructed to encircle and enclose the body of a wearer, the garment having an arm receiving opening, means for holding the garment against riding up on the body of the wearer, the holding means including an extensible member engaging the garment at the opening, guiding means to provide a turning point approximately at the waist of the garment, the member extending from the opening and through the guiding means at the turning point and being positionable to extend around the waist of the wearer and means within the garment for engaging the member extended about the waist of the wearer to place the member in tension for imparting a lateral pull to the member at the waist and to place the member between the opening and the guiding means in tension to impart a downward pull upon the garment at the opening.

2. In combination with a garment of the shirt or waist type, wherein the garment is constructed substantially to enclose the torso and has means for receiving the arms of the wearer therethrough, extensible means anchored to the gar-

ment at the arms-receiving means, the extensible means being positionable about the body of the wearer to place the garment in tension on the body of the wearer at the waist, and guiding means on the garment for the extensible means, the guiding means being below the arms-receiving means and approximately at the waist, the extensible means passing through and being free to move in the guiding means, the extensible means, when placing the garment in tension around the waist, exerting a downward pull toward the guiding means on the anchorages at the arms-receiving means.

3. In combination with a garment of the shirt or waist type, wherein the garment is constructed substantially to enclose the torso and has passages for the arms of the wearer, extensible means anchored to the garment at the passages, the extensible means being positionable about the body of the wearer to place the garment in tension on the body of the wearer at the waist, and guiding means on the garment for the extensible means, the guiding means being below the passages and approximately at the waist, the extensible means being retained by but being free to move with relation to the guiding means, the extensible means, when placing the garment in tension around the waist, being turned by the guiding means from a direction to encircle the waist to a substantially vertical direction to exert a downward pull toward the guiding means on the anchorages at the passages.

4. In combination with a garment of the shirt or waist type, wherein the garment is constructed substantially to enclose the torso and has passages for the arms of the wearer, an extensible member anchored to the garment at each of the passages, the members being within the garment and being capable of extension from the anchorage points about the body of the wearer, and guiding means on the garment for the members, the guiding means being below the passages and approximately at the waist, the members being retained by but free to move with relation to the guiding means, the members providing means, when placed in tension about the body of the wearer and within the garment, to clamp the garment at the guiding means snugly against the body of the wearer and to exert a downward pull toward the guiding means on the anchorages at the passages.

5. In combination with a garment of the shirt or waist type, wherein the garment is constructed substantially to enclose the torso and has passages for the arms of the wearer, an extensible member anchored to the garment at each of the passages, the members being within the garment and being capable of extension from the anchorage points about the body of the wearer, and guiding means on the garment for the members, the guiding means being below the passages and approximately at the waist, the members being retained by but being free to move with relation to the guiding means, the members, when extended about the body of the wearer and secured to each other and placed in tension, providing means to clamp the garment at the guiding means snugly against the body of the wearer and to exert a downward pull toward the guiding means on the anchorages at the passages.

6. In combination with a garment of the shirt or waist type, wherein the garment is constructed substantially to enclose the torso and has passages for the arms of the wearer, an exten-

sible member anchored to the garment at each of the passages, the members being within the garment and being capable of extension from the anchorage points about the body of the wearer, and guiding means on the garment for the members, the guiding means being below the passages and approximately at the waist, the members being retained by but being free to move with relation to the guiding means, the members extending down from the anchorages at the passages and past the guiding means and then laterally away from the guiding means around the body of the wearer and, when secured to each other and placed in tension, providing means to clamp the garment at the guiding means snugly against the body of the wearer and to exert a downward pull toward the guiding means on the anchorages at the passages.

7. In combination with a garment of the shirt or waist type, wherein the garment is constructed substantially to enclose the torso and has armholes for the arms of the wearer, an elastic member anchored to the garment approximately at the lowermost portion of the edge of each of the armholes, the members being within the garment and being capable of extension from the anchorage points about the body of the wearer, and guiding means on the garment for the members, the guiding means being below the armholes and approximately at the waist, the members being retained by but being free to move with relation to the guiding means, the members extending down from the anchorages at the armholes and past the guiding means and then laterally away from the guiding means around the body of the wearer and, when secured to each other and placed in tension, providing means to clamp the garment at the guiding means snugly against the body of the wearer and to exert a downward pull toward the guiding means on the anchorages at the armholes.

8. In combination with a garment of the shirt

or waist type, wherein the garment is constructed substantially to enclose the torso and has armholes for the arms of the wearer, an elastic member anchored to the garment approximately at the lowermost portion of the edge of each of the armholes, a sheath extending downwardly from the edge of each of the armholes and housing the elastic member, a band secured to the elastic member and extending outside of the sheath within the garment and about the body of the wearer, the sheath having an opening at its lower end and at least approximately at the opening being secured to the garment, the secured-together band and member being movable through the opening, the sheath at the opening providing guiding means for the members and the bands, the openings being approximately at the waist, the secured-together bands and members extending down from the anchorages at the armholes and past the openings and then laterally away from the openings around the body of the wearer and, when the bands are secured to each other and placed in tension, providing means to clamp the garment at the openings snugly against the body of the wearer and to exert a downward pull toward the waist on the anchorages at the armholes.
